UNITED STATES PATENT OFFICE.

JAMES T. LAUGHLIN, OF BOISE, IDAHO.

EYEGLASS-MOUNTING.

1,161,699.

Specification of Letters Patent. Patented Nov. 23, 1915.

Application filed May 8, 1912. Serial No. 695,811.

To all whom it may concern:

Be it known that I, JAMES T. LAUGHLIN, a citizen of the United States, and resident of Boise, in the county of Ada and State of Idaho, have invented certain new and useful Improvements in Eyeglass-Mountings, of which the following is a specification.

This invention relates to eye-glass mounting and is an improvement on my Reissue 10 Patent No. 13394, and has for its object to provide simple and effective means whereby the pupillary distance between the lenses may be reduced to the minimum in so-called finger piece mountings by pivoting the nose 15 grips to the rear of the plane of the lens instead of on the bridge member in line with the lens as is usually done.

A further object of the invention is to provide upwardly extending diverging 20 yieldable engaging guard members connected to the nose grips to coöperate therewith, said extensions being adapted to engage the supra-orbital arches of the wearer and provide a greatly extended engaging 25 and gripping area, thereby assisting in retaining the glasses in position and permitting the pressure of the nose grips to be reduced to the minimum.

With these and other objects in view, the 30 invention consists of certain novel features of construction, as will be more fully described and particularly pointed out in the appended claims.

Of the accompanying drawings Figure 35 1— is a greatly enlarged front elevation showing my improved construction of glasses. Fig. 2— is a top edge view showing a portion of the bridge, one of the lenses, and my improved nose grip as pivoted to 40 the rear of the lens. Fig. 3— is an edge elevation sectioned through the bridge member and showing my improved nose grip as pivoted to the extension on the rear portion of the lens clamp. Fig. 4— is a top view 45 showing a detail of one of the lens clamps with the pivot supporting extension connected to the rear portion thereof. Fig. 5— is a top or plan view of the nose grip showing the pivoting ear attached thereto.

50 Referring to the drawings, 1 designates the bridge portion, each end of which is provided with a lens clamp 2, which clamps are usually forked to receive the lens 3 between the branches, the lens being retained 55 therein against the strap 5 by means of the screw 4.

One of the features of my invention is that an extending pivot receiving ear member 6 is connected to the rear portion of each lens clamp, the same being provided with a threaded screw hole 7 and an upwardly extending pin 8 against which the end of the spring presently described is adapted to rest.

The essential feature of my invention is 65 the construction of the nose gripping members each of which is preferably made of a single piece of wire or metal and provided with a laterally projecting pivot receiving portion 9 which may be formed integral 70 with or a separate member secured to the nose grip, the same being adapted to extend over and be pivoted to the ear member 6. The nose engaging portion of these grips are formed by bending the wire downward from 75 the pivoting point as at 10 into the form of a loop, the ends 11 of each then projecting upward and outward, in a continuous curve, and gradually decreasing in thickness, said ends being flattened to form yieldable 80 diverging arms adapted to follow the contour of the sides of the nose and extend upward and outward to engage the inner curves of the supra-orbital arches, whereby the engaging and gripping area is greatly ex- 85 tended thereby permitting the spring pressure of the grips against the nose to be reduced to the very minimum.

The end of each guard member is preferably formed slightly cupped or spoon-shaped and extremely thin and pliable so that they will yield when the eyebrows are drawn downward and so prevent dislodgment of the glasses.

In order that these nose grips may be 95 readily manipulated I have provided finger pieces 12 which extend forward from the pivoting point preferably over and clear 100 of the bridge member 1, the same being preferably bent downward so as to come directly in front of the lens clamp whereby these finger pieces are practically hidden and rendered inconspicuous. Each of these nose grips may be pivoted in position by the screw or post 13 which is reduced at its 105 lower end forming a suitable shoulder and passing through the ear 9 is threaded through the hole 7 or otherwise secured in the ear member 6. The nose grip actuating spring 14 is wound around or otherwise connected to the upper portion of this screw or post, one end of the spring being retained 110

by engaging the small pin 15, while the opposite end engages the nose grip member to hold the same normally in its closed or engaging position.

5 By my improved construction of pivoting the nose grips at the rear of the plane of the lenses it will be seen that I can shorten the bridge member very materially over the construction where these grips are pivoted 10 directly upon the bridge member. This shortening of the bridge enables me to reduce the pupillary distance between the lenses which is of advantage particularly where the use of large lenses is necessary or 15 desired.

By forming the finger piece, nose grip, and guard all of a single piece of wire or metal, a very practical, yet inexpensive construction is provided, and also enables the 20 frames to be conveniently and properly shaped and fitted to individual wearers.

I claim:

1. An eyeglass mounting comprising a pair of lens clamps, a bridge member having 25 a central arched portion, the ends of

said bridge at the terminating portions of the arch proceeding directly from said clamps, a rearwardly extending portion on the rear side of each of said clamps, and nose clamps pivotally attached to the extensions of the lens clamps and having finger pieces extending forwardly over said bridge member.

2. An eyeglass mounting comprising a pair of lens clamps, a bridge member having 30 a central arched portion, the ends of said bridge at the terminating portions of the arch proceeding directly from said clamps, an ear member extending rearwardly from the rear branch of each of said clamps, a nose clamp arm pivoted to each of said ear members and extending forwardly in a loop form over said bridge, and a closing spring acting on each arm.

In testimony whereof I affix my signature 35 in presence of two witnesses.

JAMES T. LAUGHLIN.
